UNITED STATES PATENT OFFICE.

WARREN D. HUSE, OF LACONIA, N. H., ASSIGNOR TO O. TWOMBLEY, OF LAKE VILLAGE, N. H., AND T. S. NOWELL, OF BOSTON, MASS.

KNITTING-MACHINE.

SPECIFICATION forming part of Letters Patent No. 271,071, dated January 23, 1883.

Application filed September 4, 1882. (No model.)

To all whom it may concern:

Be it known that I, WARREN D. HUSE, of Laconia, county of Belknap, and State of New Hampshire, have invented an Improvement in 5 Knitting-Machines, of which the following description, in connection with the accompanying drawings, is a specification.

My present invention is an improvement upon the apparatus shown in my Patent No. 10 255,996, dated April 4, 1882, and has for its object to reciprocate the tappet-rings by the direct action of gearing, rather than by a cam-plate such as shown in the said patent. The knitting mechanism employed will be the same 15 as in my Patent No. 220,924, October 28, 1879.

Figure 1 represents in side elevation, with portions broken away, a sufficient portion of a knitting-machine to enable my invention to be understood; Fig. 2, a sectional elevation, partially broken out; Fig. 3, a broken detail, showing a portion of the tappet-rings and part of the mechanism for moving them, with the upper end of rod R, to be referred to; and Fig. 4, a diagram of the pattern which will be formed by 25 the cam shown in the drawings, with the pins removed, however, from one of the tappet-rings.

In this invention I have marked the different parts common to my Patent No. 255,996 with like letters, and hence I need not specifically 30 describe the operation of the said parts, as they are fully described in my said patent, further than to say that A represents the needle-cylinder; B, the dial-plate; B², the cam-cylinder for the vertical needles; E F, the tappet-rings; 35 i i, their adjustable pins; D, the disk; h h, its tappet-projections; N, the rack-bar; e, gear-wheel; f, the pinion moved by the said gear-wheel; g, a crank-pin thereon; C, the rotating thread-guide; p, a pinion on the shaft of the 40 thread-guide; M, a cam; S, a sprocket-wheel; Q, a Jacquard chain; O, a reciprocating bar or rod; K, pawl-lever; l, pawl; J, wiper; H, cog-wheel; j k, transmitting-gear, and I an eccentric, all common to the said patent.

45 In the present drawings, in Fig. 2 I have also shown part of the rod R, common to my Patent No. 255,996. This rod will be lifted by the projections of the Jacquard chain Q, as in the said patent, and for the purposes described 50 in the said patent, and also for the purposes described of the rod designated by like letter

in my Patent No. 220,924, dated October 28, 1879, so the same need not be herein further described.

In Fig. 3 I have shown the top of the rod R 55 in place in the usual notch between the rings E F, having the tappet-pins i, as in said patents.

Instead of the cam-plate P, which in the said patent acts upon arms extended from the said tappet-rings, I now provide each of the said 60 tappet-rings, at its under side, with rack-teeth e², (see Fig. 1,) suitable to be engaged by the gears 3 4, the gear 3 engaging the teeth of the inner tappet-ring, F, and the gear 4 engaging the teeth of the outer tappet ring, E. 65

The gears 3 4 are secured respectively to sleeves 5 6, held in brackets 9 10, the said sleeves having also fixed to them respectively, outside the supporting brackets, gears 12 13. The gears 12 13 are engaged by the teeth of a 70 rack-bar, 14, connected with the upper end of the sliding rod or bar O, referred to, it being guided in a guide, 15. The rack will be drawn down and the foot of the rod O will be kept against the cam M by means of a spring, 16. 75

The cam M herein shown has four throw-points to raise the rack-bar gradually and let it fall quickly, and when both tappet-rings are employed such cam, by gradually lifting the bar O, will effect such movement of the rings 80 as to cause their pins to be gradually separated from each other a little farther for each course of knitting entering into the figure, so that were the pins set at a distance apart to knit two stitches for the commencement of a spot 85 the last course of the spot, by reason of the separation of the pins, might contain from ten to twenty stitches, thus making a nearly triangular spot, and when the bar drops from the end of the cam the short course for the next 90 spot will be commenced next to the broad part or base of the nearly triangular spot. By removing the pins from one of the tappet-rings, thus throwing it out of operation, the cam M, by gradually lifting the bar O, will cause the 95 tappet-ring which is yet provided with pins to gradually change its position with relation to the needle-bed, so that the pins will actuate the yarn-guide at a different point, or opposite different needles for each course of the spot or 100 figure, thus inclining the figure gradually to the right or to the left, according to which tap-

pet-ring is permitted to retain its pins, thus making a figure of equal width from end to end, as in Fig. 4. The number of pins in the tappet-rings will depend upon the number of 5 times that the yarn-guide is to be shifted for each course of knitting, each change of the 10 yarn-guide causing a yarn of different color to appear on the right side of the fabric, and the distance between the said pins will depend upon 15 the number of stitches which it is desired to make with a yarn of one color on the right side of the fabric before changing the yarn-guide to present to the needles a yarn of a different color for the right side of the fabric, the 20 yarn-guide containing yarns of two colors—as, for instance, a pin having changed the yarn-guide to present a blue yarn for the face of the fabric, another pin may be set at a distance from it to come into operation after four stitches 25 have been taken, when the yarn-guide will be again changed to present to the needle for the face of the fabric, say, a white yarn; but the next pin, or the one to again change the yarn-guide to again present the blue yarn, may be 30 at such a distance from the pin which caused the yarn-guide to present the white yarn as to permit the needles to make twenty stitches with the white yarn on the face of the fabric, so that each course of knitting would present 35 four blue and twenty white stitches in succession on the face of the fabric. Thus it will be seen that by changing the pins toward or from each other, so as to move the thread-guide sooner or later, a great variety of figures may be produced, the figures depending for their outline upon the number of stitches made in each course by the yarns of different color.

The shape of the cam M may be varied at

will, according to the shape of the figure to be produced upon the fabric being knitted.

By the employment of a gear, as described, to move the tappet-rings, I am enabled to operate the said rings more steadily and uniformly and with less friction.

I claim—

1. The tappet-ring provided with teeth, and gear to engage the same, and the rack-bar, and connecting mechanism between the said gear and rack-bar, combined with means to move the rack-bar, substantially as described.

2. The thread-guide, rack-bar to move it, the disk D, provided with tappet-projections, and means between the disk and rack-bar to move the latter, and a tappet-ring provided with teeth e^2 , the pins i on the tappet-ring, a cam, M, slide-rod, and rack, combined with a gear to engage the teeth of the tappet-ring, and with connecting means between the said gear and the rack-bar, substantially as described.

3. The two tappet-rings provided at their under side with rack-teeth, and the pins i, carried by the said rings, and a thread-guide and disk D, and means between the disk and thread-guide to actuate the latter, combined with the pattern-cam, means to move it, the sliding rack 14, gears 3 and 4, and intermediate gear between the said rack and gears 3 4, substantially as shown and described.

In testimony whereof I have signed my name to this specification in the presence of two subscribing witnesses.

WARREN D. HUSE.
